UNITED STATES PATENT OFFICE.

JAMES G. BAILEY, OF DELAVAN, ILLINOIS.

HAY-RACK.

1,155,783.

Specification of Letters Patent.

Patented Oct. 5, 1915.

Application filed December 17, 1910. Serial No. 597,791.

To all whom it may concern:

Be it known that I, JAMES G. BAILEY, a citizen of the United States, residing at Delavan, in the county of Tazewell and State of Illinois, have invented certain new and useful Improvements in Hay-Racks, of which the following is a specification.

This invention has reference to certain new and useful improvements in hay-racks and relates particularly to that form of rack having a slideable-section and a fixed-section, said slideable-section arranged to be moved longitudinally of the rack-frame and above said fixed-section.

The improvements herein have special reference to a hay-rack patented by me on August 9, 1910, No. 966,418, although such improvements may be found useful when applied to other and different forms of hay-racks. In the patent referred to, the use of mechanically operated means for moving the slideable-section after receiving its load, was done away with, and the rack-frame so constructed that the slideable-section would travel from a position above the fixed-section to a position at the opposite end of the frame by gravity. Such a construction has considerable advantage and has been found very useful and practicable, unless the front end of the rack-frame is headed up an incline or is disposed higher than the rear end of said frame, when gravity is not sufficient to accomplish the result aimed at. However, I have found the percentage of cases very small where gravity would not do all it was intended to do, but to meet such conditions I have applied the improvement herein shown and described.

Figure 1 is a longitudinal sectional view of the rack, the running-gear and wheels shown in dotted lines and the forward end of the frame shown slightly elevated above the rear end thereof. Under normal conditions, the position of the frame ends would be reversed; Fig. 2 is a perspective view of a portion of the forward portion of the rack-frame and slideable-section, showing the means for manually propelling the slideable-section, and Fig. 3 is a detail of a part of the rear end of the rack-frame.

Like characters of reference denote corresponding parts throughout the figures.

Reference is here had to the structure shown and described in my Patent No. 966,418, which it is thought will obviate the

necessity of detailing at great length the rack structure and its fixed and slideable-sections.

The rack-frame is referred to generally as 1, suitably supported on cross-frames 2 and 3 and said cross-frames are adapted to rest and be carried on the running-gear of a wagon, similar to that shown in dotted lines in Fig. 1. The construction and arrangement of the frame parts are preferably such, that the forward end of the frame is normally below the rear end, whereby when the slideable-section of the rack is at the rear end of the frame and it is released it will move to the forward end of the frame by gravity.

The fixed-rack-section is referred to generally as 4 and preferably includes approximately the rear half-section of the main frame. The slideable-rack-section is referred to generally as 5 and preferably covers approximately the front half-section of the main frame and is adapted to be moved to and fro on said main frame and over the fixed-rack-section 4. The object of which has been very clearly set forth in my Patent No. 966,418.

For locking the movable-rack-section 5 in a position above the fixed-rack-section 4, and also after it has been returned to the forward end of the frame, there is provided a longitudinal beam 6, preferably disposed centrally of the main frame and approximately the length of the forward half section of the rack-frame. To the forward end of the frame parts of the movable-rack-section 5, are pivotally connected at 7, uprights 8, which are connected or braced by cross-braces 9, 10 and 11, while pivotally connected to the brace 9 is a lever 12 which extends upwardly to a suitable point and is carried through a guide 13 on the brace 10 for maintaining said lever in an operative position.

The lower end of lever 12 extends down to a suitable point where it may be moved to a point in front of the forward end of the beam 6 or to a point in front of the rear end of said beam, and when so placed, it will be apparent that the movable-rack-section cannot be moved in either direction until after said lever has been moved to one side or the other of either the forward or rear end of the beam 6, and that if desirable, when the movable-rack-section is moving from the rear to the forward end of the frame with a load of hay, the operator who

may be upon the top of said load, may operate the lever for producing a frictional engagement between the lower end of the lever and the side of the beam 6 for retarding the return movement of said movable rack-section.

The upper edge of the beam 6 is shown provided with a series of teeth 14, preferably in the form of ratchet-teeth, and said 10 teeth may or may not be cut or formed in the beam. 15 designates a lever fulcrumed at 16 in arms 17 carried by the brace 10 and on the lower end of the lever 15 is pivoted a member 18 having the function of a pawl 15 which is adapted to engage the teeth 14 on beam 6 for manually moving or propelling the slideable-rack-section on the frame. The lever 15 is carried out beyond the lever 12 so as not to interfere with the action of said 20 lever 12, and the member 18 is an open structure, see Fig. 2, to permit the operation of the lever 12 through said member. Operating lever 15 will move the movable-rack-section in a step by step movement, and 25 to lock the rack-section when the member 18 is moved from engagement with one tooth to another, I provide the member or pawl 19, pivotally attached to the cross-piece of the movable-rack-section 5, which will drop into 30 a tooth 14 of the rack and thereby prevent backward movement of the movable-rack-section. The member or pawl 19 and the member 18 are capable of being moved out of the way when the movable-rack-section is 35 moved toward the rear end of the frame. It will be observed that when the frame is in position to correspond to Fig. 1, and the movable-rack-section 5 will not return by gravity, that a person may by manipulating 40 lever 15, move the said section to its forward position on the frame, and said section traveling on rollers, see Patent No. 966,418, will not be difficult to move.

Reference being had particularly to Fig. 45 3, 20 denotes a rear post, there being two in actual use, one at each corner of the fixed-rack-section serving as a partial inclosure for the hay after being pitched upon the fixed-section of the rack. I have found that 50 where such posts are used, if they are not movable or adjustable, the hay will get caught on the posts and the operator must be continually clearing the posts. To obviate this difficulty, I have hinged the posts 55 20 at 21 to the frame and connect a spring 22 to the lower end of the post and to the frame, see Fig. 3. The spring 22 maintains the post in a normal, upright or vertical position, but will permit the upper end of the 60 post to give and move in the direction shown in Fig. 3. Thus, it will appear that when hay is being pitched or thrown onto the rack-sections and some of it gets entangled in the post 20, the post will give to the 65 movement of the hay and as soon as the hay

releases itself, the post through the action of the spring 22 will return to its normal position.

What I claim is:—

1. A hay rack including in combination, 70 a fixed section and a section movable thereon, said second section being adapted to be moved from one end of the fixed section to the other by gravity, and means for positively moving said movable section on said fixed section, said means including a toothed bar on one of said sections, a lever on the other of said sections having a ratchet member adapted to engage said toothed bar so as to move said section. 75

2. A hay rack including in combination, a fixed section and a section movable thereon, said second section being adapted to be moved from one end of the fixed section to the other by gravity, and means for positively moving said movable section on said fixed section, said means including a toothed bar on one of said sections, a lever on the other of said sections having a ratchet member adapted to engage said 80 toothed bar so as to move said section, and means adapted to engage the sides of the toothed bar to operate as a brake or to be moved in front of either end of said bar to 85 serve as a lock. 90

3. In a hay-rack, the combination with a fixed and a movable-section under normal conditions adapted to be moved from one end of the rack to the other by gravity, of a toothed-bar disposed longitudinally on the rack, a lever carried on the movable-section, an open pawl attached to the lever and adapted to have a ratchet engagement with the teeth on the bar, a locking-member pivotally attached to the movable-section and adapted to engage the teeth on the bar for locking the movable-section in adjusted position, and a second lever carried on the movable-section, said second lever operating 100 through the open pawl on the first lever and arranged to engage the side of the bar or be moved in front of either end of said bar, for 105 purposes described. 110

4. In a hay-rack, the combination with a fixed and movable section, said movable section under normal conditions adapted to be moved from one end of the rack to the other by gravity, of a toothed bar disposed longitudinally on the rack, a frame pivoted to 115 said movable section and comprising uprights connected by cross-braces, arms extending from one of said cross-braces, a lever pivoted between said arms, an open pawl attached to said lever and adapted to have a ratchet engagement with the teeth on said bar, a locking member pivotally attached to 120 said movable section and adapted to engage the teeth on the bar for locking the movable section in adjusted position, a second lever carried by said frame, a guide therefor 125 130

one of said cross-braces, said second lever extending through the open pawl and arranged to engage the side of said bar or to be moved in front of either end of said bar for the purposes described.

5. In a hay-rack, the combination with a fixed and movable section, said movable section under normal conditions adapted to be moved from one end of the rack to the other 10 by gravity, a tooth-bar disposed longitudinally on the fixed section, a frame pivoted to the movable section and comprising uprights connected by cross-braces, a lever piv-

oted between said uprights and a pawl attached to said lever and adapted to have a 15 ratchet engagement with the teeth of said bar, whereby said movable section may be positively moved from one end of the rack to the other.

In testimony whereof I affix my signature, 20 in presence of two witnesses.

JAMES G. BAILEY.
